THERAPEUTIC, GRAVITY ACTUATED, SUS-TAINED PRESSURE APPLICATOR

Marion A. Mulkin, Kirksville, Mo.

Application March 5, 1956, Serial No. 569,451

7 Claims. (Cl. 128—68)

This invention relates generally to a therapeutic instrument and, more particularly, to an instrument for the application of therapeutic pressure to portions of the human anatomy, especially the paravertebral tissues.

An extremely effective technique for reflex treatment of spinal nerves involves the inhibition of the muscular branch of the spinal nerve and the sympathetic chain ganglia through application of continuous pressure of substantial magnitude to the paravertebral tissues for a considerable period of time without release or variation. The classic manner of performing the treatment is for the pressure to be applied manually to the proper portions of the patient's anatomy by the operator administering the treatment. The preferred pressure is from about 30 to 50 pounds depending upon the extent of tension encountered in the patient and the preferred period of treatment will similarly vary from about 5 to 35 minutes. The manual method has, however, certain obvious and significant disadvantages. First, it is virtually impossible to maintain a continuous and unvarying pressure of uniform magnitude by manual means over the required period of time. Secondly, it is extremely difficult and tiring for the operator to attempt to manually maintain a pressure of the magnitude required for a period sufficient to give optimum benefit to the patient. Thirdly, the presence and attention of the operator is required continuously during the period of treatment.

For these reasons, the classic or manual method of performing the mentioned treatment has fallen into general disuse. Even more significantly, however, since there has not been available any fully satisfactory alternative method or instrument for performing the treatment, the treatment itself has fallen into disuse, despite the universally recognized benefits which it can produce when properly performed.

It is, therefore, the primary object of this invention to provide an instrument by which the application of the desired, sustained therapeutic pressure may be effectively and conveniently accomplished without any of the disadvantages inherent in the manual method of treatment or in attempts to use instruments primarily intended for other purposes.

Reference is made to my prior application Serial No. 386,187, filed Oct. 15, 1953; now Patent Number 2,803,244, and entitled "Therapeutic Gravity Actuated Sustained Pressure Applicator." The device of my said prior application utilizes a number of the principles employed in this invention and is capable of operating in a satisfactory manner productive of worthwhile results. From a structural standpoint, however, the improved present construction about to be described is believed to possess many unexpected advantages over my said previous invention, both as to safety, operating convenience and effectiveness of performance. Accordingly, it will be un-

2

derstood that the present invention contemplates certain important improvements of a structural nature over the device of my said previous application.

Equipment heretofore proposed and designed for other purposes is inherently ill adapted for use or modification to achieve the results sought and attained by this invention, since such prior forms of equipment are either dangerous to the patient, incapable of applying and maintaining the required pressure in the proper manner, 5 not adapted for accurate and convenient adjustment of the pressure to be applied to any of several areas of the human body to be treated in connection with different ailments, or still requires the vigilant and substantially continuous attention of the operator.

Accordingly, it is another important object of the present invention to overcome such disadvantages of prior instruments primarily intended for different purposes by providing an improved instrument for the application of therapeutic pressure, wherein the pressure is applied entirely by gravity actuated means that automatically maintains the pressure being applied constant over any desired period despite respiration and variations in the resistance offered by the patient's tissues due to decreasing muscular tension during treatment, and 20 wherein means are provided for accurate preselection or adjustment during use in discreet steps of the pressure being applied. It may be noted that, for the treatment to be successful, it is essential that the applied pressure be slowly applied and released and sustained in steady, rather than jerky or uneven fashion during the period of treatment.

It is another important object of the invention to provide such apparatus which will be entirely safe in use and cannot through malfunction impose an excessive pressure which would be injurious, or even fatal to the patient, such as might occur through malfunction in apparatus utilizing extrinsic force actuating means rather than gravity.

It is another important object of the invention to provide such apparatus which is of simple nature requiring practically no maintenance and which can be quickly and inexpensively manufactured.

Still other important objects of the invention including its adaptability for safe and effective operation without the constant attendance of an operator, will be made clear or become apparent as the following description thereof progresses, it being noted that certain details of construction are deemed to be significant.

In the accompanying drawing:

Fig. 1 is a side elevational view of the entire instrument with parts being broken away and shown in section for clarity of illustration;

Fig. 2 is a cross sectional view taken on line II—II of Fig. 1; showing the pressure applying assembly of the instrument from an end thereof;

Fig. 3 is a cross sectional view taken on line III—III of Fig. 2;

Fig. 4 is a fragmentary cross sectional view taken on line IV—IV of Fig. 1;

Fig. 5 is a fragmentary elevational view of the control means for a timer device which may be conveniently installed as a part of the instrument; and

Fig. 6 is a schematic representation of the hydraulic portion of the instrument.

Referring now to the drawing, the improved structure contemplated by the preferred embodiment of the present invention is generally designated by the numeral 10, such numeral being used to indicate the instrument as a whole,

Instrument 10 includes a preferably mobile base 12, which may be mounted, for instance, upon a number of caster wheels 14. Shiftably mounted upon and protruding from the base 12 is a swingable foot pedal 16 operably connected with a liquid pump 18 for operating the latter. Base 12 houses a receptacle 20 for a supply of hydraulic fluid 22, and the inlet of pump 18 is placed in communication with fluid 22 by a conduit 24 extending into receptacle 20.

Rigidly mounted upon base 12 adjacent one end thereof is an upright, elongated, tubular, cylindrical post 26. Pump 18, which is also housed within base 12, communicates through a conduit 28, a check valve 30 and a conduit 32 within the inlet port 34 of a hydraulic or pneumatic cylinder 36 disposed within post 26 and provided with a piston 38 having an upwardly extending rod 40 connected thereto. The body of cylinder 36 is obviously secured to the base and post structure 12-26, while the rod 40 is free to reciprocate relative thereto.

At the uppermost end of rod 40 is secured a spider 42, which includes a number of upwardly extending arms 44 on which is supported the uppermost closed end 46 of an elongated, upright, tubular, cylindrical sleeve 48 telescopically mounted on the post 26 for vertically reciprocable, sliding movement relative to the latter.

A control valve 50 is mounted within sleeve 48 adjacent top 46 thereof, and top 46 is provided with an opening 52 for clearing a control shaft 54 coupled with the valve 50 and extending outwardly of sleeve 48 through opening 52 to a control knob 56 provided on the uppermost end of the shaft 54.

An exhaust port 58 in cylinder 36 below the piston 38 is coupled by a conduit 60 with the control valve 50 which is in turn coupled with a return conduit 62 for carrying fluid 22 from the cylinder 36 back to the receptacle 20 when the valve 50 is opened. For reasons which will hereinafter become more apparent, valve 50 is preferably of the needle type so that the flow of fluid 22 from cylinder 36 may be accurately controlled and limited to a slow rate of flow.

Extending upwardly and laterally from the sleeve 48 is an arm 64, such arm 64 being either formed integrally with the sleeve 48 or secured thereto in any conventional fashion. Arm 64 includes an outermost horizontal portion 66 provided with a vertical bore 68 therethrough having a stretch of enlarged diameter at 70. A vertical shaft 72 having an uppermost threaded portion 74 and a down-turned shoulder 76 extends through bore 68, and a complementally threaded locking knob 78 is disposed above arm portion 66 upon threaded portion 74 of shaft 72. Shaft 72 is mounted for free rotation within bore 68 by a ball bearing assembly generally designated 80 having an upper race 82 press fitted upon shaft 72 immediately below shoulder 76 and a lower race 84 upon which race 82 is supported by bearing balls 86. Bearing structure 80 is disposed and freely rotatable within enlarged portion 70 of bore 68 and is secured to arm portion 66 by a plate 88 underlying race 84, provided with an opening 90 for clearing shaft 72, and secured to arm portion 66 by screws or the like 92.

A yoke generally designated 94 has a neck 96 provided with a bore 98 into which shaft 72 extends, neck 96 being secured to shaft 72 by a pin 100 passing therethrough. As will be apparent, when the locking knob 78 is loosened upon threaded portion 74 of shaft 72, the yoke 94 may be freely rotated relative to the arm 64; however, when the knob 78 is tightened upon thread 74 to draw the upper extremity of neck 96 into tight frictional engagement with the lowermost surface of retaining plate 88, the yoke 94 will be rigidly held in a desired position of rotation. It may be noted that the relationship between shoulder 76 of shaft 72 and the bearing assembly 80 held by plate 88 insure against dropping of the yoke 94 and its associated structure in the event that the thread 74 on shaft 72 should become stripped.

As will be most clear in Fig. 1, yoke 94 is bifurcated and includes a pair of elongated, spaced, parallel legs 102 and 104 depending below the arm portion 66 in a substantially vertical direction. Adjacent their lowermost ends, legs 102 and 104 are respectively provided with openings 106 and 108 for receiving an elongated horizontal shaft 110 extending between legs 102 and 104 and through the latter.

Rotatably mounted upon shaft 110 between arms 102 and 104 is a generally rectangular, rigid, metallic plate 112 provided with a bore 114 through which shaft 110 passes. Plate 112 has a pair of major faces 116 and 118, the former being concave and the latter being convex. Secured upon concave face 116 of plate 112 is a soft, pliable layer or pad 120, which may be formed of sponge rubber. Secured upon pad 120 opposite plate 112 is a resilient, but relatively firm, layer or pad 122, which may be formed of ordinary rubber. Pads 120 and 122 conform to the concavity of face 116 presenting a slightly concave surface 124 upon pad 122 opposite the plate 112. Similarly, a soft pliable pad 126 is secured upon the convex face 118 of plate 112, and a firm, resilient pad 128 is secured upon pad 126 opposite plate 112 and having a slightly convex treating surface 130 thereon.

Plate 112 is provided with a cylindrical extension 132 adjacent leg 104, and leg 104 is provided with a laterally projecting, annular flange 134, extension 132 and flange 134 having opposed, serrated faces as at 136.

The end portion of shaft 110 passing through leg 104 is threaded as at 138 to receive a complementally threaded locking knob 140. A washer 142 upon shaft 110 between plate 112 and leg 102 is designated 142 and is held against movement longitudinally of shaft 110 by a cotter pin 144.

As will now be apparent, when the knob 140 is loosened upon threads 138, the shaft 110 reciprocates in the direction of leg 102 freeing the serrations 136 of extension 132 and flange 134 from each other so that plate 112 and its associated parts, which are generally designated 146 for purposes of identification, may be freely rotated upon the shaft 110 to dispose either the concave face 124 or the convex face 130 of assembly 146 downwardly or at a desired angle for contact with a patient during treatment. The convex face 130 on assembly 146 has been found particularly advantageous in treating portions of a patient's body where the tissue to receive pressure are disposed within a concavity of the anatomy, while the concave face 124 possesses similar advantages for treating portions of a patient's body having a substantially flat or convex external contour.

When the valve 50 is closed, operation of the pump 18 by foot pedal 16 will result in fluid 22 being forced into cylinder 36 to raise the piston 38 and thereby the sleeve 48 upon the post 26. As long as the valve 50 remains closed, the sleeve 48 will be retained in substantially any position of elevation upon the post 26. When, however, the knob 56 is operated to open valve 50, fluid 22 will flow from cylinder 36 permitting piston 38 and sleeve 48 to descend until the assembly 146 has come into contact with the body of a patient by which the sleeve 48 will be held against further descent upon post 26. Obviously, with the valve 50 open sleeve 48 is freely slideable upwardly or downwardly upon the post 26 so that the pressure exerted upon a patient's anatomy by the assembly 146 depends entirely upon the inherent weight of sleeve 48, the arm 64, the yoke 94, the assembly 146 and various other parts carried thereby including those now to be described.

At its lowermost end, sleeve 48 is provided with an internal groove 148 for receiving a complemental flange 150 upon a cylindrical, tubular weight element 152 slidably mounted upon post 26 below sleeve 48. Successively additional weight elements 154, 156 and 158, which are identical in construction to the element 152 are provided upon the post 26 below sleeve 48 and weight 152,

each of such elements 152, 154, 156 and 158 having an internal groove 160 at its lower extremity similar to the groove 148 of sleeve 48 for receiving the complementary, upstanding flange 162 of the underlying element 154, 156 or 158.

The sleeve 48 and each of weight elements 152, 154 and 156 is provided adjacent its lowermost end with an L-shaped slot 164 adapted to releasably receive therein a radially extending bolt or the like 166 threadably secured in the flange portion 148 or 160 of the underlying weight element 152, 154, 156 or 158.

As will be clear from the drawing, weight element 152 may be releasably secured or easily detached from the sleeve 48 to add its weight to the latter simply by lifting the element 152 to move the bolt 166 into the slot 164 and then rotating the element 152 to position bolt 166 in the horizontal portion of the slot 164. In similar fashion the weight element 154 may be releasably attached to or detached from the weight element 152, etc. It is significant that the lowermost extremity of sleeve 48 must be spaced above the base 12 sufficiently to permit the storage of any of the weight elements 152, 154, 156 and 158 in a position upon base 12 disengaged from the sleeve 48 and spaced from the lower end of the latter or the lower end of the lowermost one of elements 152, 154, 156 and 158 which is coupled with the sleeve 48. If it is desired to releasably lock the elements 152 et seq. to the sleeve 48 or the overlying one of said elements, as the case may be, the bolt 166 on the underlying element may be tightened until it holdingly engages the overlying sleeve 48 or element 152, 154 or 156. It may be noted that even if a particular one or more of the elements 152 et seq. should be inadvertently disconnected from its overlying supporting structure, the patient could not be thereby injured since the pressure applied would be decreased, rather than increased.

In a preferred embodiment of the invention, the sleeve 48, arm 64, yoke 94, assembly 146 and minor parts associated therewith (excluding the weight elements 152, 154, 156 and 158) are so constructed as to have a weight of 30 pounds. The weight elements 52, 54, 56 and 58 are each formed to have a weight of 10 pounds each. Thus, by the addition of one or more of the weight elements 152, 154, 156 and 158 by coupling same with the sleeve 48 or the next overlying weight element the aggregate weight transmitted to pressure applying assembly 146 may be conveniently and quickly varied from 30 to 70 pounds in increments of 10 pounds. Obviously, the weight elements 152, 154, 156 and 158 could be of other or differing weights to provide other incremental choices of variation.

Since the treatment to be given with the apparatus 10 is normally for a predetermined period of time, it has been found convenient to install within the arm 64 a timing mechanism (not shown) having a bell or other alarm (not shown) as a part thereof, such mechanism being provided with an adjustment knob 170 mounted upon arm 64 for setting the time to elapse before the warning bell (not shown) alerts the attending operator to the fact that the desired time has elapsed. A graduated dial 172 is mounted upon the arm 64 for cooperation with the setting knob 170.

In operation, the sleeve 48, an appropriate number of weight elements 152, 154, 156 and 158 attached to sleeve 48, the arm 64 and assembly 146 are raised to dispose the latter at an elevation higher than the patient by the manipulation of foot pedal 16 to operate pump 18 while the valve 50 is closed. Base 12 is then shifted on wheels 14 to dispose assembly 146 over the portion of the patient's anatomy to which pressure is to be applied, and the assembly 146 is adjusted in the manner previously explained to dispose surface 124 or 130 in proper orientation. Then, the valve 50 is opened slightly to permit the assembly 146 to settle slowly down upon the patient as the sleeve settles upon the post 26. As soon as the

assembly 146 is resting upon the patient, the valve 50 should be opened wide to permit absolutely free reciprocation of the sleeve 48 upon the post 26 for reasons hereinbefore explained. When the period of treatment is over, the valve 50 may be closed and the pump pedal 16 again operated to raise the assembly 146 off the patient.

It will now be apparent that the apparatus described is ideally suited for accomplishing all of the objectives and overcoming all of the difficulties hereinbefore mentioned. It will also be apparent that certain minor modifications and changes could be made from the exact structure shown and described for purposes of illustration without departing from the true spirit and intention of the invention. Accordingly, it should be understood that the invention shall be deemed limited only by the scope of the appended claims.

Having thus described the invention, what is claimed as new and desired to be secured by Letters Patent is:

1. In the therapeutic, gravity actuated, self-sustained, constant pressure applicator, a base; an upright post on the base; a sleeve slidably mounted for free vertical reciprocation on the post; a laterally extending arm on the sleeve; a patient-contacting, pressure-applying assembly 20 on the arm and depending therefrom, said sleeve, arm and assembly being of predetermined weight, the pressure applied to the patient being developed by the applicator alone solely through the action of gravity; and fluid system means for raising the sleeve on the post to lift the assembly out of contact with the patient, said means being releasable to permit free reciprocation of the sleeve on the post during treatment of the patient.

2. In a therapeutic, gravity actuated, self-sustained, constant pressure applicator, a base; an upright post on the base; a sleeve slidably mounted for free vertical reciprocation on the post; a laterally extending arm on the sleeve; a patient-contacting, pressure-applying assembly 25 on the arm and depending therefrom, said sleeve, arm and assembly being of predetermined weight, the pressure applied to the patient being developed by the applicator alone solely through the action of gravity; and fluid system means for raising the sleeve on the post to lift the assembly out of contact with the patient, said means being releasable to permit free reciprocation of the sleeve on the post during treatment of the patient.

3. In an applicator as set forth in claim 2, wherein said elements are normally disposed in vertically stacked relationship, and there is provided means for releasably locking the uppermost element to the sleeve and each remaining element to the element immediately thereabove.

4. In a therapeutic, gravity actuated, self-sustained, constant pressure applicator, a base; an upright post on the base; a sleeve slidably and rotatably mounted on the post for free rotation and vertical reciprocation relative to the latter; a laterally extending arm on the sleeve; and a patient-contacting, pressure-applying assembly 55 on the arm and depending therefrom, said sleeve, arm and assembly being of predetermined weight, the pressure applied to the patient being developed by the applicator alone solely through the action of gravity.

5. In a therapeutic, gravity actuated, self-sustained, constant pressure applicator, a base; an upright post on the base; a sleeve slidably mounted for free vertical reciprocation on the post; a laterally extending arm on the sleeve; a patient-contacting, pressure-applying assembly 65 on the arm and depending therefrom, said sleeve, arm and assembly being of predetermined weight, the pressure applied to the patient being developed by the applicator alone solely through the action of gravity, said assembly being mounted on the arm for rotation about a substantially vertical axis; and means for releasably locking the assembly against rotation about said vertical axis.

6. In a therapeutic, gravity actuated, self-sustained, constant pressure applicator, a base; an upright post on

the base; a sleeve slidably mounted for free vertical reciprocation on the post; a laterally extending arm on the sleeve; a patient-contacting, pressure-applying assembly on the arm and depending therefrom, said sleeve, arm and assembly being of predetermined weight, the pressure applied to the patient being developed by the applicator alone solely through the action of gravity; and means mounting said assembly on the arm for rotation about a substantially horizontal axis.

7. In an applicator as set forth in claim 6, wherein is provided means for releasably locking the assembly against rotation about said horizontal axis. 10
